UNITED STATES PATENT OFFICE

CAROLUS M. COBB, OF LYNN, MASSACHUSETTS

POWDER DISTRIBUTOR

Application filed March 12, 1928. Serial No. 261,133.

The invention relates to powder distributors of the type having a suitable container for holding the powder supply which is provided with a customary neck opening and cap held together by screw threads.

The invention consists of a powder distributor having suitable novel devices for preparing or breaking up the powder into its finest particles and then discharging them in suitable quantities as desired. To accomplish this, pressure suction and discharge pipes are provided both of which are rigidly secured to the cap and extend in both directions to meet the demands. The outer end 10 of the pressure suction pipe is fastened to a pressure bulb and the opposite end extends downwardly into the container within a working range of the powder supply. The outer end of the discharge pipe serves as a nozzle 15 to deliver the powder and the opposite end inside the container is turned up sufficiently to provide an indirect flow of powder in the path of the powder stream to obtain the desired density and quantity of powder and 20 also to prevent it from spilling if the container takes an inverted position. The flow of powder is determined approximately by the size of the opening in the discharge pipe and the rate of pressure used to force the 25 powder against the atmosphere at the discharge end. When the pressure bulb expands, it draws in air from the outside of the container through the discharge pipe and thence to the pressure bulb through the pressure suction pipe. The drawing in of the 30 air tends to clean all the pipes of powder preparatory for the next discharging operation. The pulling in and discharging of the air saturated with powder keeps it broken up 35 into its finest particles so it will flow or float through an indirect discharge pipe for application.

The object of the invention is to provide a powder distributor having a certain flow, 40 pressure and density of air and powder which will allow it to pass off in an indirect stream to obtain an even distribution of the powder and also to prevent it from discharging large globules of powder, and to cut out all methods 45 of wasteful distribution.

A further object of the invention is to provide a powder distributor that can be used in the trades, arts, medicine and surgery, and for all kinds of toilet preparations.

Referring to the figures which illustrate 55 the embodiments of my invention showing like numerals throughout the figures to indicate corresponding parts:

Figure 1 is a side elevation of my improved indirect powder distributor. 60

Figure 2 is a side elevation of the same enclosed in a suitable casing or cover.

Figure 3 is a modified view of the intake device for the indirect discharge pipe.

Figure 4 is a modified view of the intake 65 device for the indirect discharge pipe.

Referring to the drawings which illustrate my improved indirect discharge powder distributor secured to a container, 10 indicates a container having a powder supply 11 there- 70 in. The container is provided with an opening neck 12, having screw threads 13 formed on its outer surface. Cooperating with the neck 12 and threads 13 is a threaded cap 14 screwed over the opening in the neck 12 to 75 prevent the powder from leaking or spilling out. Rigidly secured to the cap 14 is a pressure suction pipe 15 and a discharge pipe 16. The pipes 15 and 16 are held rigidly in position by solder 17. The pipes extend in 80 both directions to facilitate the operation of the device. The outer end 18 of the pipe 15 is bent back into a predetermined position and is secured to the pressure bulb 19. The opposite end 20 of the pressure suction pipe 15 85 extends downwardly into a working range with the powder supply 11. The upper end 21 of the discharge pipe 16 serves as a nozzle for delivering the powder. The lower end of the discharge pipe 16 is bent upwardly as 90 indicated by the numeral 22, and provides an indirect entrance 23 for the powder to pass off and at the same time prevent large glob- 95 ules from entering the discharge pipe which would destroy the efficiency of the device. It also prevents powder from spilling out of the discharge pipe if the container was turned upside down. There are many ways of providing an indirect flow entrance of a discharge pipe and in addition to the one shown 100

in Figures 1 and 3 is a modified construction shown in Figure 4, consisting of the pipe 16 which is plugged at 24 and a hole 25 machined in the side of the pipe as indicated on the drawing.

5 The device can be used as shown in Figures 1 and 3 or it can be enclosed in any suitable casing or bag. I have shown the distributor in a bag 26, Figure 2, made of any suitable material such as cloth or leather.

10 In operation the powder distributor has a container 10 for holding the powder supply 11. Working in conjunction with these elements is a cap 14 having a pressure suction 15 pipe and a powder discharging pipe. The bulb 19 is connected to the pressure suction pipe 18, and is constructed without valves so that air or any fluid when drawn in, is forced to enter through the discharge pipe 16, causing the air to be saturated with powder to help to break it up into its finest particles and at the same time clear out all the pipes preparatory to a powder discharge. 20 The discharging of air and powder by the pressure bulb serves as a blast for breaking up the powder and suspending it sufficiently so that it will flow off in the path of the discharge stream through the indirect entrance 23 of the discharge pipe 16 to the delivery end of the applicator. The indirect entrance to the discharge pipe serves to prevent the powder from spilling out through the discharge pipe if the container is turned upside down.

25 What I claim as new and desire to secure by Letters Patent of the United States is:

1. A powder distributor comprising a powder container, a pressure bulb for forcing air, an air pipe extending from the pressure bulb into the lower part of the container the lower end having a free opening to permit the powder to be drawn in and out of the pipe to prevent it from forming into lumps, a discharge pipe extending into the upper part of the container only, and means in the discharge pipe to cause the powder to flow indirectly into it for an even distribution.

40 2. A powder distributor comprising a powder container, a pressure bulb for forcing air, an air pipe extending from the pressure bulb into the lower part of the container the lower end having a free opening to permit the powder to be drawn in and out of the pipe to prevent it from forming into lumps, a discharge pipe extending into the upper part of the container only, and an upturned end of the discharge pipe inside the container to cause the powder to flow indirectly into it for even distribution.
